UNITED STATES PATENT OFFICE.

OSCAR GRENIER AND JULIEN GRAND, OF LYONS, FRANCE.

APPARATUS FOR GENERATING ACETYLENE GAS.

SPECIFICATION forming part of Letters Patent No. 606,539, dated June 28, 1898.

Application filed October 29, 1896. Serial No. 610,465. (No model.) Patented in France March 30, 1896, No. 255,154; in England August 12, 1896, No. 17,904; in Italy September 28, 1896, LXXXIII, 445; in Belgium September 30, 1896, No. 123,596; in Luxemburg October 9, 1896, No. 2,623; in Spain November 21, 1896, No. 19,695; in Switzerland February 28, 1897, No. 13,068; in Austria July 8, 1897, No. 47/2,649, and in Hungary July 15, 1897, No. 8,552.

To all whom it may concern:

Be it known that we, OSCAR GRENIER and JULIEN GRAND, engineers, citizens of the Republic of France, residing at Lyons, in the Republic of France, have invented certain new and useful Improvements in and Relating to Apparatus for Generating and Utilizing Acetylene Gas for Lighting Purposes, (for which Letters Patent have been granted in 5 France, No. 255,154, dated March 30, 1896; in Great Britain, No. 17,904, dated August 12, 1896; in Austria, No. 47/2,649, dated July 8, 1897; in Belgium, No. 123,596, dated September 30, 1896; in Spain, No. 19,695, dated November 21, 1896; in Italy, Vol. LXXXIII, No. 445, dated September 28, 1896; in Switzerland, No. 13,068, dated February 28, 1897; in Luxemburg, No. 2,623, dated October 9, 1896, and in Hungary, No. 8,552, dated July 15, 1897,) of which the following is a specification, reference being had to the accompanying drawings.

Our invention relates to gas-generating apparatus to which we give the name of "an acetylene-producer," the purpose thereof being the generation of illuminating acetylene gas from suitably-prepared carburet of calcium. In constructing the said acetylene-producer the object has been to provide a simple apparatus in which the production of acetylene gas should take place in proportion to the requirements of the consumption in a methodical manner without having in the presence of water an excess of calcium carburet. In order to realize this result, it was necessary to employ calcium carburet in a special form, insuring the measuring off of the smallest quantities, and for this purpose the use of calcium carburet in grains of a definite size was absolutely necessary. In fact, by the crushing of calcium carburet to grains of known dimensions passing through a sieve of definite fineness, according to the exigencies of the distribution, a product is obtained which an appropriate distributor can divide into exact portions designed to give rise, by their contact with the water, to a

known volume of acetylene gas for each portion. The importance of such a rational employment of calcium carburet will be understood at once. The mass intended to cause the generation of gas is not all placed in the presence of water at once, as this would occasion a tumultuous and too rapid and abundant production, which would carry away 55 watery vapors and would continue to a point where it would be useless and dangerous.

It is not necessary to set forth all the inconveniences and all the dangers which result from the immediate action of water upon a mass of calcium carburet. It may, however, be stated that by effecting a partial distribution of calcium carburet in water it is our intention to completely isolate the calcium carburet from the ambient action, and thus 65 obviate the decomposition of its mass in the presence of moisture, to avoid the excess of production of the gas and the pressure, (occasioning a loss of gas or an accident,) and also to preclude the fear of the ever-possible presence of calcium phosphuret in the mass of carburet placed in contact with water. On the other hand, it is preferable to keep the calcium carburet in its solid form, when it is an excellent accumulator of gas and portable energy, and which presents real advantages as compared with acetylene gas stored up in gas-holders or liquefied under pressure, inasmuch as this necessitates, in the first place, comparatively large gas-holders, and, in the 75 second place, receptacles which are at the same time heavy, strong, and dangerous to handle, occasioning expenses for maintenance, transport, and liquefaction which solid carburet in the form of grains does not necessitate, 85 and which gives instantly acetylene with the acetylene-producer by a simple operation of a cock.

As far as we are concerned and as regards the distributor which we use, the calcium carburet is crushed to grains of the size of from one to two millimeters and bolted in sieves insuring these two sizes. All fine powder is rejected. Accordingly it is the grain

of from one to two millimeters on the side in respect of which we claim operative results from this special form of distributor.

The invention is illustrated in the accompanying drawings, in which—

Figures 1 and 1^a are central vertical sections of an apparatus in which our invention is incorporated. Fig. 2 is an elevation of the entire apparatus, drawn to a reduced scale.

10 The distributor D, as shown in Fig. 1 of the drawings, has the form of a sand-box and is based upon the principle of the running of solids along inclinations determined by experiment.

15 In order that the comminuted carburet of calcium may not choke while passing out of its receptacle, we make the plug of cylindrical form, with a smooth surface and uniform taper.

20 The central cylinder O, which is from twenty to twenty-five millimeters in diameter and acts as a hopper, is of the same diameter as the cone C, which closes the outlet-orifice and which is actuated by a powerful spring 25 R, always tending to close the same.

The cylinder O is arranged in the center of the distributor D, the latter having a uniformly-contracted lower portion, which terminates at the discharge-opening closed by 30 the plug C. The lower end of the central cylinder O is immediately over said opening.

The spring which forces the cone upon its seat is placed in the cylinder O and kept from all contact with the contents of the distributor.

35 Lastly, the central cylinder regulates the outlet of the carburet by limiting the thickness I of carburet in the form of a grain which will pass upon the cone C of the distributor.

40 in order to insure the mathematically-accurate dosing of the grains to be distributed.

The distance e from the lower edge of the hopper-cylinder O to the side of the distributing-funnel D should be at least half the 45 radius of the outlet-orifice.

The distributing-plug C has not only the function of closing the distributor, but also that of regulating the discharge and even that of provoking it if, in consequence of an 50 agglomeration of the solid material forming an arch upon the outlet-orifice, the distribution should cease.

It is impossible to obtain a certain, uniform, and regular discharge of carburet in 55 the form of grains unless the distributing-plug is connected to an agitator which forces the material toward the outlet-orifices and breaks any arch which may tend to be formed in the mass.

60 The distributor, having a conical plug and a valve-seat upon which said plug closes and provided with a powerful spring insuring the closing of said plug, is actuated by two levers L L, to which two or more spatulae S are 65 fixed. The spatulae consist of long narrow strips having their upper ends attached to an annular plate L², which is suspended in the

upper part of the distributor by means of two levers L L, which are pivotally connected at their ends to projections l l, which rise from a cross-plate l² a little below the levers. The said levers lie parallel to each other, one on each side of the diametrical line of the distributor, their movable ends being near the opposite sides of the distributor and against the lower surface of the bell K. Their pivoted ends pass the center of the distributor before they reach their points of pivotal attachment, and the annular plate L², which supports the spatulae, is suspended from pawls 70 not far from the movable ends of the levers. The proportions of the levers L are such that the spatula traverse double the way of that which the central cylinder O moves and impart to the material upon the inclined plane 85 V of the funnel a movement of translation toward the outlet-orifice, so as to insure a distribution which is always certain and practically uniform in quantity. We conclude, then, on this point by stating that the methodical 90 distribution of calcium carburet in the form of grains of from one to two millimeters in a distributor having the form of a sand-box is insured by the mechanical pushing of the carburet in conjunction with the upward movement of the distributing-cone, which, so to speak, "compels" the grains of carburet to pass out without turning back and without deviation of the outrunning vein toward the decomposition-water. This distribution, thus 95 defined and clearly represented in the accompanying drawings, defines the new elements of this invention.

In order to operate the mechanism for controlling the acetylene-gas producer, we can 105 use, practically, only the pressure obtained by the acetylene gas produced. It is necessary, therefore, to cause this pressure to act upon the greatest possible surface if a force is to be produced sufficient for effecting the 110 desired result.

The bell of the gas-holder is the largest valve that can be made, because it has the dimensions of the apparatus itself. It is the 115 pressure-regulator and is balanced for the working pressure of ten to twenty centimeters of water, according to the circumstances of the case. Any increase in the volume of gas produced is stored up in the bell without 120 enabling the pressure to be modified, and if an undesired disengagement of acetylene gas should take place the entire orifice of the bell would serve for its discharge without any possible accident.

For the decomposition of the calcium carburet we employ the water-reservoir B, and for holding the generated gas we provide the vessel A, which is entirely distant from the water-reservoir. In the vessel A we provide an annular water-chamber a, in which the 125 bell K is located. With this arrangement no escape is possible between the vessel and the bell, because the acetylene is produced in a distinct reservoir. Any liquid which does

- not congeal, such as glycerin, may be used in the vessel A, and if the height of the bell is to be diminished mercury can be substituted. Should there be a pressure of gas which would 5 drive the water out of the vessel, there will be no occasion to fear the projection of muddy water, such as would take place in case the bell were put directly upon the water of the decomposition-reservoir B.
- 10 We not only simplify the apparatus by the construction set forth, but as the carburet in the form of powder always remains perfectly dry by reason of its nature there is no need of a special closing device when the distributor D is placed inside the apparatus, as all 15 odors are confined by the vessel A. As the bell K is not fixed to any part of the apparatus, it is controlled like a safety-valve only by the action of the interior pressure of the 20 gas and by its own weight. Under these circumstances nothing can interfere with its action as a regulator and as a safety-valve having a large orifice, thereby insuring the absolute security of the acetylene-producer.
- 25 As already stated, the water-reservoir B for the decomposition of the carburet is distinct from the vessel A of the gas-holder, and this is absolutely necessary if the regular and certain operation of the bell is to be insured.
- 30 This independence, moreover, enables us to easily increase the diameter of this reservoir, and thus increase the volume of water used in the decomposition. Under these circumstances the temperature for heating the acetylene, in conjunction with the weight of carburet distributed, is properly regulated when they work normally, and, according to the 35 conditions given, a rise of only two degrees in temperature per hour of work is found to take place.
- 40 The reservoir B has a water-inlet G and an exhausting-outlet P to draw off the lime-milk. The vessel A is provided with a gage N and the reservoir B has a gage N' for indicating 45 the height of water in the apparatus.
- 45 The use of the plug Z for withdrawing the contents of the vessel B will only be necessary at long intervals. On the bell K there is a charging-hopper M, provided with upper and 50 lower valves.
- 55 The acetylene produced should be washed and freed from the water-vapor which it contains and also from the solid foreign particles which it may carry away mechanically. We therefore arrange a washer T in the interior of the gas-holder, between the wall of the vessel A and a concentric circular wall T'. This washer T is placed upon an annular diaphragm U, as shown in the drawings. It is 60 filled with sponges T², which dip in the water at the lower part of the washer and are kept moist by absorption, and iron turnings, coke-dust, charcoal, and glass-wool are placed in the annular space of the washer. The gas 65 generated passes into this washer and through the multiple channels of the different stratified porous materials therein and then trav-

erses the moist sponges, which retain all the solid particles carried away, washing the acetylene which has reached this point thoroughly. 70

A large drying-tube H is mounted on one side, and its lower end enters the top of the water-reservoir B. Said end is open for the entrance of the washed gas, and the interior 75 of the tube is provided with numerous perforated diaphragms Y, on which we place absorbent material Q, such as dry sponge, glass-wool, and pieces of calcium carburet to remove the water and other impurities from 80 the gas, so that it arrives in the burners clean and dry. The diaphragms Y may be of wire-gauze supported by an axial rod X.

What we claim is—

1. An acetylene-gas producer, comprising 85 a generating vessel having an enlarged lower portion containing water, a bell having its open lower end placed in an annular chamber containing a suitable fluid and raised above the water-chamber, a distributor rigidly supported in said bell and provided with a funnel-shaped lower end, a spring-closed, tapered plug to close the outlet at said lower end, and means actuated by the opening of said plug to break up any choking of the 90 granulated material and feed the latter in uniform quantities to the gas-generating chamber, substantially as described.

2. In an acetylene-gas producer, the combination with a generating-chamber containing water of a bell rising above the said generating-chamber, its open lower end lying in a fluid in an annular chamber arranged above the water, a distributor rigidly supported in the upper part of said bell and having a 100 funnel-shaped lower end, a tapered, spring-pressed plug to close the outlet in said lower end, a central, vertical cylinder to inclose the spring acting on said plug, a plurality of spatulae hanging in said funnel-shaped end, 110 levers pivoted at the top of the distributor to support said spatulae their movable ends resting on the under surface of the closed top of the bell, and a stem in the central tube having its upper end connected to and rising 115 above the levers between their pivoted ends and the points of suspension of the spatulae, substantially as described.

3. In an acetylene-gas producer, the combination with a generating-chamber of a bell 120 rising above the same, its open lower end lying in fluid in an annular chamber above the generating-chamber, a distributor having a funnel-shaped discharge end, a central tube inclosing a spring, a tapered plug connected 125 to the spring and seated by it in the outlet, spatulae suspended in the distributor with their ends a little above the outlet, levers pivoted at their ends in the upper end of the distributor and having the spatulae suspended 130 from them at points between the pivoted ends and free ends, and a stem connected to said levers and to the spring-seated plug, substantially as described.

4. In an acetylene-gas producer, the combination of the water-reservoir B having thereon the drier-cylinder II provided with perforated diaphragms Y, the annular water vessel A having the bell K inverted therein and supported above the reservoir B, the annular washer-chamber T supported in and concentric with the vessels A and B, the suspended distributing vessel D, a spring-actuated plug C to control the discharge-orifice of said distributing vessel D, and spatulae S

suspended in said distributing-vessel from levers connected with the vertically-extended stem of the said plug, substantially as described.

15

In testimony whereof we have hereunto set our hands this 9th day of October, 1896.

OSCAR GRENIER.
